ANIMATED TOY

Ralph B. Stewart, Chevy Chase, Md.

Application July 30, 1932, Serial No. 626,758

12 Claims. (Cl. 46—40)

This invention relates to toys and in particular to animated toys suitable for use as targets in various games employing projectiles thrown or propelled against the target.

An object of my invention is to devise a toy having the shape of an animal and provided with an energy storing device latched in energy stored position by a target latch, the arrangement being such that when the target latch is tripped to release the stored energy, the toy is caused to act in some manner simulating the action of an animal.

Four forms of my invention are shown in the accompanying drawings in which the toy simulates the form of a rabbit and in which the tripping of the target latch causes the rabbit to jump over backwards.

Figure 1 of the accompanying drawings is a front view of one form of my invention;

Figure 2 is a side view of Figure 1;

Figure 3 is a plan view of Figure 1;

Figure 4 is a side view of Figure 2 after the target latch has been tripped;

Figure 5 is a side view partly in section, of a second form of the invention;

Figure 6 is a sectional view of Figure 5 along line 6—6;

Figure 7 is a side view, partly in section, of a third form of the invention;

Figure 8 is a sectional view of Fig. 7 along line 8—8;

Figure 9 is a side view, partly in section, of a fourth form of the invention;

Figure 10 is a sectional view taken along line 10—10 of Figure 9.

Referring to Figures 1 and 2, one form of the invention comprises a body portion 1, the outline of which is formed to represent the head and the body of a rabbit. It is obvious this portion may be formed to represent any other animal. The body portion 1 is pivotally mounted on a base portion by means of a pin 2. The base portion comprises two side members 3 and 4 secured to a bottom member 5, the two side members being formed to simulate the hind legs of a rabbit in a squatting position. An energy storing device such as a spring wire 6 has a looped portion engaging a notch 7 in the body portion 1 and is formed in convolutions around pin 2 on both sides of the body portion. The end portions 6a and 6b of spring 6 rest on the base member 5, thereby tending to produce a rotating movement of the body 1 about the pin 2 in a clockwise direction. A U-shaped link 8 pivoted by means of shanks 8a and 8b in the side members 3 and 4 is engaged

by another U-shaped link 9 which in turn is pivoted in the front of the body 1 as at 10. The link 9, in passing through the body portion at 10, also serves as a pivot for supporting a target or trigger element 11, which is formed of a metallic channel piece embracing the front edge of the body portion. With the body portion 1 in the position as shown in Fig. 2, the plane of link 8 lies to the right of the pivot axis 10, and the link 9 has a tendency to rotate about pivot 10 in a clockwise direction, forcing the horizontal portion of link 8 against trigger 11 and into latched position against the body portion. Any force, such as the impact of a projectile 12 against the lower end of the trigger 11, forces the link 8 to the left of pivot 10 thereby releasing the latch, and the energy in the spring 6 causes the body to rotate about the pin 2 to a position as shown in Fig. 4. In order to release the latch the trigger 11 must be moved by the projectile so that the plane of link 8 passes to the other side of axis 10 from the position shown in Fig. 2. The energy stored in the spring 6 is expended in storing kinetic energy in the rotating movement of the body about the pin 2. When the link mechanism has reached a position as shown in Fig. 4, further rotation is stopped by the link 8 engaging the lower end of trigger 11, and the kinetic energy of the rotating body causes the whole toy to jump and rotate in a clockwise direction. By proper design the toy can be made to perform in several different manners. It will be clear that the following factors, among others, enter into consideration in the design: Location of the centers of gravity of the body and base portions; the relative weights of the two portions; the strength of the energy storing spring; and the angle of rotation of the body portion. Preferably these factors are so selected that the toy will jump up, make one revolution, and land on the base again.

In the modifications shown in Figures 5 to 10 the latch and rotation limiting structures are enclosed within the body portion in order to reduce the possibility of injury to those using the toy. In these figures elements like those in Figures 1 and 2 are indicated by the same reference characters. For the sake of clearness of illustration, the energy storing spring has been omitted from Figures 5 to 10.

In the arrangement shown in Figures 5 and 6 the body has a cavity 13 in which is pivoted a bar link 14 by a pin 15. Secured to the base 5 is a bracket 16 the upper end of which extends partly into the cavity 13 and pivotally supports a U-shaped link 17 which passes through the

lower end of bar 14. The base portion is provided with an extension 5a in which is slidably mounted a rod 18 on the outer end of which is secured a target 19. The inner end of rod 18 passes through an opening in bracket 16 and engages the lower end of bar 14. A pin 18a prevents dislodgment of the rod 18.

The arrangement as shown in solid lines in Figure 5 is in latched position. In this position 10 the line passing through the pivot axes in the ends of bar 14 lies to the left of the pivotal axis of link 17 in bracket 16. In this position, the pull of spring through the bar 14 tends to rotate the link 17 in a clockwise direction, but the rotation 15 is restrained either by pin 18 or by the upper end of the bracket 16. Upon striking the target 19 by a projectile, the rod 18 moves the bar 14 so that the line passing through the pivotal points on the bar lies to the right of the pivotal axis of 20 the link 17, thereby releasing the latch. The body portion is then rotated to the position shown in dotted lines at 1a, the links 14 and 17 then occupying the position shown in dotted lines at 14a and 17a, respectively. It will thus be seen 25 that the links 14 and 17 serve both as a latch and as a rotation limiting element.

In the arrangement shown in Figures 7 and 8 the cavity 13 in the body portion receives the upper end of a link 20 which is pivoted in the 30 upper end of bracket 16. The upper end of the link 20 is made into arcuate form and is provided with a slot 29a, and the lower end of this slot is enlarged to form a hook for engaging a pin 21 passing through the body portion 1. The engagement of the hook portion over the pin 21 serves to latch the body portion against rotation. The lower end of bar 21 terminates opposite the inner end of rod 18.

The manner of operation of Figure 7 is believed to be clear. A projectile striking the target 40 19 drives a rod 18 against the lower end of link 20, thereby causing the hook to disengage the pin 21 and release the body portion 1. As the body rotates, the pin 21 travels along the slot 29a until it reaches the end of the slot where it restrains further rotation of the body. In order to render the arrangement self-locking, the link 45 20 should be designed so that the center of gravity lies above and to the right of the pivotal axis in bracket 16.

In the arrangement shown in Figures 9 and 10 separate structures are provided to perform the latching function and the rotation limiting function. The latch structure comprises a link 22 55 pivotally supported in cavity 13 in the body portion. The lower end of link 22 extends downwardly to a point opposite the end of rod 18 and is provided with a hook portion 22a which engages a loop 23 secured to the base 5. The rotation limiting structure comprises a link 24 pivotally secured in side members 3 and 4, and a link 25 60 pivotally secured in the body portion 1 and having pivotal connection with the link 24, as shown.

In the operation of Figures 9 and 10, the rod 65 18 moves the hook portion of the bar 22 out of engagement with the loop 23 and the body is rotated until the links 24 and 25 restrain further rotation. The toy may be relatched by simply pressing down the body 1, the lower end of the link 22 being formed at an angle to ride over the loop 23. A pin 26 is provided to prevent the link 22 from moving to the left of the loop 23. Preferably, the pivotal axis of link 22 should lie to the 70 left of the line passing vertically through the loop 23.

In the arrangements shown in Figures 5 to 10, a weak spring may be inserted between the target 19 and the extension 5a to return the target to its normal position.

The link arrangements forming the latch and rotation limiting devices of Figures 1 to 4 and 5 and 6 may be considered as a modified toggle joint. The ordinary toggle joint is usually employed to connect two members between which a biasing force acts tending to force them together. In the present arrangements, the links are connected between two members between which a biasing force acts tending to separate the members. In this sense, the link arrangements may be said to constitute an inverse toggle arrangement.

It will be obvious to those skilled in the art that many changes in the details of my invention may be made without departing from the spirit of the invention.

What I claim is:

1. A target device comprising, a base portion, a body portion pivoted to said base portion, energy storing means tending to rotate said body portion with respect to said base portion, and a trip latch target for releasing said energy storing means, said trip latch including means for limiting the relative rotation of said body portion and said base portion when rotated by said energy storing means.

2. A target device comprising in combination a base portion, a body portion pivoted to said base portion, energy storing means tending to produce relative rotation of said portions, a trip latch target for releasing said energy storing means, said trip latch including means to limit the relative rotation of said portions when rotated by said energy storing means, the energy stored in said energy storing device being sufficient to produce an angular velocity of the body portion with respect to the base portion in the limited angular rotation sufficient to turn over the whole of said target device.

3. In a toy, the combination of an animal-shaped body portion pivoted to a base portion, energy storing means tending to rotate said body portion with respect to said base portion, a link mechanism for latching said body portion to said base portion, a trigger target arranged to unlock said link mechanism and allow the body portion to rotate with respect to said base portion, said link mechanism including means to positively limit the rotation of said body portion to a predetermined angle.

4. In a target device, a base portion having side members, a body portion pivoted to said base portion, energy storing means tending to rotate said body portion with respect to said base portion, a link pivoted in said side members, another link pivoted in said body, said links being pivotally connected together, said links being arranged to lock said body portion against rotation when said body portion is placed in energy storing position with respect to said base portion, and a target member for tripping said links.

5. In a target device, a base portion having side members, a body portion located between said side members and spaced therefrom, a pin passing through said side members and said body portion for pivotally securing said portions together, an energy storing spring having a central looped portion engaging the body portion, and end portions extending into the spaces between said body portion and said side members and passing around said pin in the spaces on the two sides

of said body portion and engaging said base portion, and a trip latch target for latching said body portion to said base portion in energy storing position.

5. In a target device, a base portion having side members, a body portion located between said side members and spaced therefrom, a pin passing through said side members and said body portion for pivotally securing said portions together, 10 an energy storing spring comprising a wire having convolutions surrounding said pin in the spaces on each side of said body portion, said convolutions being joined by a central looped portion engaging the body portion, and the terminal portions of said convolutions being arranged 15 to engage said base portion for producing relative rotation between said base and body portions, a trip latch target for latching said body portion to said base portion in energy storing position, 20 said trip latch including two cooperating elements for limiting the relative rotation between said base and body portions.

6. In a target device, a base portion, a body portion pivoted to said base portion, energy storing means tending to rotate said body portion with respect to said base portion, a link pivoted to said base portion, another link pivoted to said body portion, said links being pivotally connected together and being arranged to lock said body portion against rotation when said body portion is placed in energy storing position with respect to said base portion, and a target member for tripping said links.

7. In a target device, a base portion, a body portion pivoted to said base portion, energy storing means tending to rotate said body portion with respect to said base portion, a link pivoted to said base portion, another link pivoted to said body portion, said links being pivotally connected together and arranged so that when said body portion is moved into energy storing position with respect to said base portion said links fold back upon each other and lock said body portion against rotation with respect to said base portion, one of said links being under tension and the other under compression in locked position, and a target member for tripping said links from latched position.

8. In a target device, a base portion, a body portion pivoted to said base portion, energy storing means tending to rotate said body portion with respect to said base portion, a link pivoted to said base portion, another link pivoted to said body portion, said links being pivotally connected together and arranged so that when said body portion is moved into energy storing position with respect to said base portion said links fold back upon each other, means for maintaining said links in folded position to thereby lock said body portion against rotation with respect to said base portion, with the pivotal connection between said

links to one side of the line of centers of the pivots of said links to said body and base portions, and a target device having means for moving said pivotal connection to the other side of said line of centers.

10. In combination, two relatively movable members, means tending to cause relative movement of said members, a link pivoted to one of said members, another link pivoted to the second of said members, said links being pivotally connected together and arranged so that in one position of said relatively movable members said links fold back upon each other and lock said members against relative movement by said means, one of said links being under tension and the other under compression in locked position with the common pivot axis located to one side of the line of centers of the pivots on said members, and means for moving the common pivot axis past the line of centers to unlatch said members and permit relative movement thereof.

11. A target device comprising in combination a base portion, a body portion pivoted to said base portion, energy storing means tending to produce relative rotation of said portions, said body and base portions being provided with adjacent cavities, a link pivoted to said base portion and adapted to swing down into the cavity of said portion, a second link pivoted to the body portion in the cavity thereof and adapted to extend into the cavity of the base portion, said links being pivotally connected together and arranged so that when said body portion is moved into energy storing position with respect to said base portion, said links fold back upon each other, means for maintaining said links in folded position to thereby lock said body against rotation with respect to said base portion with the pivotal connection between said links to one side of the line of centers of the pivots of said links to said body and base portions, and a target device having means for moving said pivotal connection to the other side of said line of centers.

12. In a target device, a base portion, a body portion pivoted to said base portion, energy storing means tending to rotate said body portion with respect to said base portion, a link pivoted to said base portion and extending into a cavity formed in the body portion, the upper end of said link being provided with an elongated slot 50 having a hook-like formation at the lower end thereof, a pin passing through said body portion and arranged in the slot of said link and adapted to engage said hook formation to hold said body and base portions in energy stored relation, and a target device having means for moving said link to disengage said hook formation from said pin, and permit the rotation of said body portion to the end of said elongated slot.
